UNITED STATES PATENT OFFICE.

BRYAN P. JOYCE, OF DAVENPORT, IOWA, ASSIGNOR TO DAVID M. KING, OF THE UNITED STATES ARMY.

SAFETY LOCKING APPARATUS.

Application filed August 20, 1925. Serial No. 51,532.

(GRANTED UNDER THE ACT OF MARCH 3, 1883; 22 STAT. L. 625.)

The invention described herein may be used by the Government, or any of its officers or employees in prosecution of work for the Government, or by any other person in the United States, without payment to me of any royalty thereon, in accordance with the act of March 3, 1883.

This invention relates to a safety locking apparatus, especially designed for guns of large calibers.

In certain types of large caliber guns, it is necessary after firing each round to move the gun from its elevated or firing position to an approximately horizontal position for loading. These guns are provided with the usual elevating mechanism to which the gun cradle is locked during firing and in addition with a quick loading mechanism moving the gun rapidly to and from its elevated position to a position for loading.

According to the present invention a clutch is provided for locking the gear train between a self-locking elevating worm and the elevating arc of the tipping parts, this clutch being disengaged when bringing the quick loading mechanism into play. This arrangement is utilized for operating a device which will prevent premature actuation of the firing means when the clutch is disengaged.

The principal object then, of the invention, is the provision of an apparatus operable through manipulation of the elevating mechanism clutch which will prevent actuation of the firing means when the clutch is disengaged, while inversely it will clear the firing means when the clutch is engaged. The apparatus also includes auxiliary locking means which will function when the gun fails to return completely into battery.

To these and other ends, my invention consists in the construction, arrangement, and combination of elements, described hereinafter and pointed out in the claims forming a part of this specification.

A practical embodiment of the invention is illustrated in the accompanying drawings, wherein:

Fig. 1 is a fragmentary view in right side elevation of a gun provided with the improved locking apparatus, the parts of said apparatus being shown in position to prevent actuation of the firing means and the

gun being in battery with the clutch disengaged;

55

Fig. 2 is a transverse sectional view through the top carriage above the elevating shaft;

Fig. 3 is an enlarged detail view in elevation of the locking apparatus shown in the locking position;

Fig. 4 is a similar view of the locking apparatus showing the position of its elements when the gun is not in battery;

Fig. 5 is an enlarged elevation of the front bracket and attendant mechanism;

Fig. 6 is a sectional view on the line 6—6 of Fig. 5;

Fig. 7 is a detail sectional view on the line 7—7 of Fig. 5;

70

Fig. 8 is a reversed detail view in side elevation of the clutch lever;

Fig. 9 is a plan view thereof;

Fig. 10 is an enlarged view in elevation of the connection between the elevating shaft and the locking apparatus;

Fig. 11 is a front view thereof;

Fig. 12 is a detail sectional view on the line 12—12 of Fig. 10;

Fig. 13 is a view along the lines of Fig. 12 but showing the pusher plate in its out position; and

Fig. 14 is a detail view of the pusher plate.

Referring to the drawings by numerals of reference:

There is shown at 5 a gun reciprocally mounted on the usual cradle 6 which is trunnioned as at 7 in the bracket arms 8 of a top carriage 9.

90

The gun may be elevated by means of any suitable mechanism which in the preferred embodiment of my invention includes an elevating shaft 10 (Fig. 2) mounted in the top carriage 9 and provided with an elevating pinion 11 which is at all times in mesh with the elevating arc or segment 12 carried by the cradle. One end of a through shaft 13 within the elevating shaft 10 carries a clutch 14 splined as at 15 to the shaft 10 and provided with teeth 16 for engaging internal teeth in an elevating worm wheel 17 when the clutch is held in normal operative engagement by means of a spring 18 embracing a guide rod 13' pinned to the clutch and constituting an extension of the

95

100

105

through shaft 13. The worm wheel 17 is driven through a self-locking worm 20 actuated by a gear train generally designated by the numeral 21.

5 The quick loading mechanism by means of which the elevating pinion 11 may be more rapidly driven when the clutch is disengaged includes in the present instance a spur gear 22 fast on the shaft 10 oppositely with respect to the clutch and meshing with a spur pinion 23 which forms part of the actuating gear train in the housings 24 and 25.

15 The clutch is disengaged by moving the through shaft 13, a convenient apparatus for accomplishing this from the right side of the gun consisting of a cam 26 mounted in a bracket 27 and connected by a pivoted link 28 to a bell crank lever 29. By raising 20 the lever 29 the cam is moved forwardly imparting a sufficient inward movement to the through shaft 13 to disengage the clutch from the worm wheel.

25 The movement of the through shaft is utilized to operate a safety locking apparatus to prevent actuation of the firing means with which the gun is provided and which comprises a hammer 30 pivotally mounted on the breech block and provided 30 with an extension 31 by which the hammer may be retained in the inoperative position.

35 The safety locking apparatus consists of two separate elements, one mounted to recoil with the gun, and the other carried by 40 the top carriage so as to be capable of being actuated by the through shaft 13. The direct connection of the latter element with this shaft 13 is effected by means of a link 32 having an apertured head 33 through 45 which the shaft 13 passes. The shaft is formed with a tapered portion 34, so that, as it is moved inwardly, the link is cammed downwardly against the action of a spring 35, seated on a block 36 disposed within a slot in the link and secured to the top carriage by screws 37. The upper end of the link is attached to a sectional ring 38 assembled for rotation around a projection 39 from the top carriage at the trunnion. The 50 rear section of the ring is formed with a slot 38' adjacent the projection 39 to permit the mounting of a segmental channel pusher plate 40 of less length than the slot. This plate is mounted for radial movement 55 on a pin 41, its in and out movement being limited by engagement of its flanges with the ring. The radial movement of the plate, during which it performs a pushing operation as will be seen later, is controlled 60 through the rotation of the ring by means of a pin 42 carried by either member, in this instance by the ring and disposed in a blind slot 43 in the plate. Beveled surfaces 44 and 44' may be provided in the ring to 65 act on complementary lugs 45 and 45' of

the plate to assist in moving it. As the link 32 is pulled downwardly during disengagement of the clutch, the ring 38 is rotated a sufficient distance to cause the pusher plate 40 to assume its operative position, shown 70 in Figures 3 and 13. Upon reengagement of the clutch the plate is automatically withdrawn by reason of counter-rotation of the ring effected by the spring 33.

75 The element of the safety locking apparatus which is carried by the recoiling parts and which is actuated by the pusher plate 40 consists of a rod 46 within a sleeve 47 which is slidably supported in a pair of brackets 48-48' on the breech end of the 80 gun. Both members have limited relative movement with respect to each other under the influence of a spring 49 surrounding the sleeve and confined between a collar 50 on the sleeve, and a pin 51 carried by the rod 85 and working in a slot 47' in the sleeve. The sleeve is connected by a pin 52' to one end of a lever 52 pivotally secured at its center to the forward bracket 48' and also pinned at its other end to a shaft 53 slidably supported in this bracket. The pin 52' is disposed in a slot 48' in the rod in order to provide for movement of the rod without effecting movement of the shaft. The slot 90 47' is so dimensioned and arranged that in 95 the unrestrained position of the sliding members, the action of the spring 49 is exerted to first move the lighter rod 46 forwardly (as shown in Figure 4) until the pin 51 is brought up against the bracket. 100 Being thus restrained, the spring then acts to move the sleeve to the rear into the path of the hammer extension 31 until it is arrested by a pin 54 on the shaft 53 which contacts one of the ears of the forward 105 bracket 48'. The forward movement of the shaft positions it so that it will strike the cradle 6 on the completion of the counter-recoiling stroke of the gun and through the lever withdraws the sleeve from the path of 110 the hammer thereby enabling the hammer to be functioned only when the piece is fully in battery. Although the sleeve assumes its rear position immediately upon discharge 115 of the piece it will not interfere with the cocking of the hammer since this operation is performed with the breech block open.

120 As the gun arrives in battery the rod 46 is in its normal forward position where it is adapted to be pushed by the plate 40 when this member is moved to its outward or operative position by virtue of the clutch of the elevating gear being disengaged. The rod is consequently moved to the rear, as shown in Figures 1 and 3, where it will prevent actuation of the hammer to fire the piece. Upon reengaging the clutch thereby locking the tipping parts to the elevating mechanism, the plate 40 is withdrawn, as 125 has been previously described, and the rod 130

moves forward to inoperative position under the influence of the spring 49.

In operation, assuming the gun to be fully in battery and locked in the elevated position the rod 46 and the sleeve 47 are both in their forward or inoperative position enabling a free sweep of the firing hammer 30-31. After firing and return of the gun into battery with the rod and sleeve 10 in the same position it is necessary to depress the gun for loading. To do this the clutch 14 is disengaged by moving the through shaft 13 by means of the bell crank lever 29 whence the quick loading mechanism through the intermediation of the gears 22 and 23 may actuate the elevating shaft 10. Upon disengaging the clutch, the through shaft 13 actuates the link 32 to rotate the ring 38 and radially moves the 20 plate 40. The plate 40 thus serves to push the rod 46 to the rear to prevent operation of the firing hammer when the tipping parts are unlocked and it is only when the clutch has been reengaged that the pusher plate 25 40 is withdrawn to allow the rod to be moved forward by the spring 49 to clear the hammer. Should the loading operation be performed with the gun a short distance out of battery the rod 46 which is carried by the 30 gun could evidently not be moved to the rear by the pusher plate 40 when disengaging the clutch. It is to provide for this contingency that the sleeve 47 is normally in the operative position during reciprocation of the gun, being returned to inoperative position only when the shaft 53 strikes the end of the cradle when the gun arrives in battery.

While in the foregoing there has been 40 illustrated and described such combination and arrangement of elements as constitute the preferred embodiment of the invention, it is nevertheless desired to emphasize the fact that interpretation of the invention should only be conclusive when made in the light of the subjoined claims.

I claim:

1. The combination with a carriage and a cradle provided with a gun having firing means, of mechanism including a clutch for moving the gun to an elevated position for firing, means for moving the gun for loading independently of the elevating mechanism when the clutch is disengaged, a ring mounted for rotation on the carriage, a plate carried by the ring and adapted to be moved radially on rotation of the ring, means operable on disengagement of the clutch for rotating the ring to move the plate, means operable when the clutch is engaged for counter-rotating the ring to restore the plate, brackets on the gun, a sleeve having a collar and a slot slidably mounted in the brackets, a shaft slidable in the forward bracket, a lever pivoted to the bracket

and connecting the sleeve and shaft, a rod within the sleeve, a pin on the rod disposed in the slot of the sleeve, a spring surrounding the sleeve and confined between the collar and the pin on the rod, said spring 70 adapted to move the rod forwardly until the pin contacts the front bracket and then simultaneously move the sleeve rearwardly to prevent movement of the firing means and the shaft forwardly, means for limiting 75 movement of the sleeve and shaft, said shaft adapted to strike the cradle on return of the gun into battery to retract the sleeve, and the rod adapted to be moved rearwardly by the plate when the clutch is disengaged to prevent movement of the firing means.

2. The combination with a carriage and a cradle provided with a gun having firing means, of mechanism including a clutch for 80 moving the gun to an elevated position for firing, means for moving the gun for loading independently of the elevating mechanism when the clutch is disengaged, a pusher member on the carriage normally in inoperative position and adapted to be moved to operative position when the clutch is disengaged, a sleeve slidably mounted on the gun, a shaft connected thereto by a lever, a rod in the sleeve, a spring for moving the rod 90 forwardly and the sleeve rearwardly in the path of the firing means, means for limiting movement of the rod and sleeve, the shaft adapted to strike the cradle on return of the gun into battery to retract the sleeve, and the rod adapted to be moved rearwardly into the path of the firing means by the pusher member when the same is in operative position.

3. The combination with a cradle provided with a gun having firing means, of mechanism for moving the gun to an elevated position for firing, means for locking the gun to said elevating mechanism, a quick loading mechanism operable when the gun is unlocked, a sleeve slidably mounted on the gun, a shaft connected thereto by a lever, a rod in the sleeve, means normally moving the rod forwardly and the sleeve rearwardly in the path of the firing means, means for limiting movement of the rod and sleeve, the shaft adapted to strike the cradle on return of the gun into battery to retract the sleeve, and means operable on unlocking the gun 110 from the elevating mechanism for pushing 115 the rod in the path of the firing means.

4. The combination with a cradle provided with a gun having firing means, of mechanism for moving the gun to an elevated position for firing, means for locking the gun to said elevating mechanism, a quick loading mechanism operable when the gun is unlocked, means on the gun for preventing 125 actuation of the firing means except when the gun is in battery, and means within said 130

means adapted to be moved to prevent actuation of the firing means when the gun is unlocked from the elevating mechanism.

5. In a gun having firing means, mechanism for elevating the gun, means for locking and unlocking the gun from said elevating mechanism, a rod slidably mounted on the gun and normally clear of the firing means, and means operable on unlocking the gun from the elevating mechanism for moving the rod into the path of the firing means, said last named means including a rotatable ring and a member movable radially on rotation of the ring.
- 10 6. A cradle, a gun having firing means reciprocal thereon, brackets on the gun, a member slidable in said brackets, a shaft slidable in the forward bracket, a lever connecting said member and shaft, means for moving 20 the member rearwardly to prevent actuation

of the firing means, means for limiting said movement, and said member adapted to be retracted to clear the firing means when the shaft strikes the cradle as the gun arrives in battery.

25

7. A cradle, a gun having firing means reciprocal thereon, a member slidably mounted on the gun and normally positioned to prevent actuation of the firing means when the gun is out of battery, and means connected with said member for retracting the same when said means strikes the cradle as the gun arrives in battery.

30

8. A cradle, a gun having firing means reciprocal thereon, and means on the gun normally positioned to prevent actuation of the firing means when the gun is out of battery but adapted when the gun is in battery to be moved by the cradle clear of the firing means.
